UNITED STATES PATENT OFFICE.

CHARLES FRED SCHWARZ AND CORNELIUS L. SHADER, OF TROY, NEW YORK.

COLLAR-BAND.

1,383,343.

Specification of Letters Patent. Patented July 5, 1921.

Application filed May 22, 1920. Serial No. 383,473.

To all whom it may concern:

Be it known that we, CHARLES FRED SCHWARZ and CORNELIUS L. SHADER, citizens of the United States, residing at Troy, in the 5 county of Rensselaer and State of New York, have invented certain new and useful Improvements in Collar-Bands, of which the following is a specification, reference being had therein to the accompanying 10 drawing.

The invention relates to neck bands for collars and has for its object to provide a new article of manufacture and method or mode of operation for making neck bands, by means 15 of which time and material are saved.

A further object of the invention is to provide a neck band formed from fabric sections, the edges of which have been creased and turned in and the sections placed 20 in registration with each other and sewed together with their turned in portions toward each other, also to provide a longitudinally disposed row of stitches, spaced from the lower edge of the band which 25 stitches limit the upward movement of the edge of the shirt neck opening so that the band may be easily and properly placed on the shirt adjacent the opening.

A further object is to provide the strip 30 of material, which is disposed outwardly with a flap which is folded inwardly so as to be disposed between the sections, thereby providing a piece of material to cover the outer face of the edge of the shirt opening 35 so as to hide the raw edge and at the same time providing a pad, which pad will relieve the pressure of the collar button on the neck, and also forming an additional reinforcement for the band.

With the above and other objects in view 40 the invention resides in the combination and arrangement of parts as hereinafter set forth, shown in the drawings, described and claimed, it being understood that changes 45 in the precise embodiment of the invention may be made within the scope of what is claimed without departing from the spirit of the invention.

In the drawings:—

Figure 1 is a plan view of the blank from 50 which the outer strip of the neck band is formed.

Fig. 2 is a plan view of the outer strip 55 showing the upper and side marginal edges as having been folded in and the reinforcing extension folded in.

Fig. 3 is a plan view of the outer strip showing the bottom flap as having been folded upwardly and disposed beneath the reinforcing folds. 60

Fig. 4 is a plan view of the inner strip, showing the same before its marginal edges have been folded in.

Fig. 5 is a plan view of the inner strip showing the same after it has been folded in 65 and in condition to be placed in registration with the folded strip shown in Fig. 3.

Fig. 6 is a perspective view of the collar band showing one end ripped open to show portions of the abutting surfaces of the 70 strip.

Fig. 7 is a sectional view taken on line 7—7 of Fig. 6.

Fig. 8 is a sectional perspective view 75 taken on line 8—8 of Fig. 6.

Heretofore neck bands have been made by first marking on a strip of material, the pattern for as many blanks as the strips would cut and then stamping or cutting the blanks in accordance with the pattern. The blanks 80 so cut, then being sent to operators, who crease them by hand, and they are then sent to other operators who turn down the edges, after which the blanks are put together and sewed. By the improved method contem- 85 plated, the blanks are cut according to the pattern out of a strip of material of a size sufficient to allow one edge and portion of the end to be turned over, instead of having a blank where it is necessary to turn over 90 both edges, as is usually done in blanks heretofore made. Then the blank A is placed upon a suitable machine or die which turns the edges A' to assume the position shown in dotted lines A², Fig. 1, and shown in full 95

lines in Fig. 2. The turned in portion A' substantially centrally thereof is provided with an extension A³, which folds into two sections A⁴ on the line A⁵ to the position shown in Fig. 2, so as to form a reinforcing 100 member carried between the outer and inner strips which form the band. After the blank has been folded to the position shown in Fig. 2, the lower section A⁶ is folded upwardly and disposed beneath the reinforcing sections A⁴; then the blank is entirely formed and is in folded condition as shown in Fig. 3. The blank shown in Fig. 3, in folded position is a blank used for the outer side of the collar band. However, it will be 110 seen that after the inner and outer strips are secured together that either strip may be

outwardly disposed. The turned over portion A' is along the upper edge and sides of the blank and substantially at the same time that edge A' is turned over, the blank is creased along the medial line A⁷, shown by dotted lines in Figs. 1 and 2 and also in Fig. 4 of the other strip B, thereby causing the blank to assume the position shown in Fig. 3, in which the turned over portion A' 5 engages along its marginal edge, the marginal edge A⁸ of the section A⁶. The line which is termed the medial line A⁷, being preferably substantially equally distant from the edge A⁸ and the edge A⁹ of the 10 turned in portion A'. By referring to Fig. 3, it will be seen that all of the edges have been turned in and the strip is then creased. The blank forming the other strip of the collar band is of the same construction as 15 the blank shown in Figs. 1 to 3 inclusive with the exception that reinforcing sections A⁴ are eliminated, therefore the same reference numerals as applied to Figs. 1 to 3 inclusive apply to the strip shown in Figs. 20 4 and 5. After the strips have been so formed from blanks they are placed side by side as shown in Fig. 6 with their turned in portions or sides in engagement with each other; the strips being in engagement 25 with each other they are stitched together along their upper edges as shown at C and D, stitching D being at their ends. Stitching C and D passes through the outer layers and also through the turned in edges A'. 30 A second line of stitching E is then placed adjacent the upper edge of the band and parallel therewith. Stitching E passes through the outer layers of the material and through the inner layers of the sections A⁶ 35 adjacent the edges A⁸ thereof. Extending longitudinally of the band is a line of stitching F which is broken as at G where it passes over the reinforcing members A⁴. Stitching F is parallel with the 40 lower edge of the band and is preferably centrally disposed on the band and forms means whereby when the edge of the neck 45

opening of the garment is inserted between the folds as shown at H, it will limit the downward movement of the band on the 50 garment and will form means whereby the band may be accurately placed on the garment opening and secured in place.

From the above it will be seen that a four 55 ply neck band is provided which is equally durable, strong and serviceable as the bands made in the usual manner and that one is provided in which more blanks can be cut out of a given piece of cloth because of leaving off the material necessary to turn over 60 on one half of the blank. Time and money are saved by performing in one operation, the turning of the edges and creasing of the neck band and the bands being in position to be sewed together immediately after they 65 have been received from the operator, who has creased and turned the edges.

The invention having been set forth what is claimed as new and useful is:—

As a new article of manufacture, a neck 70 band adapted to be attached permanently by stitching to the neck opening of a shirt, said band consisting of two similarly shaped blanks, each having its upper edge and its ends turned in upon the body of the blank, 75 and each folded longitudinally on itself with its edges in abutting engagement with each other; and stitches passing through the inturned portions uniting the blanks at their upper edge, and a second line of stitches 80 passing through the blanks at a distance from the lower edges of the blanks, whereby an opening is provided for the insertion of the edge of the neck opening of the shirt, said stitches limiting the distance to which 85 the edge of the neck opening may be inserted within the opening in the neck band, and constituting a guide for positioning the band in the neck opening.

In testimony whereof we hereunto affix our 90 signatures.

CHARLES FRED SCHWARZ,
CORNELIUS L. SHADER.
